UNITED STATES PATENT OFFICE.

JEAN FRÉDÉRIC JULES REIBEL, OF CHATELLERAULT, FRANCE, ASSIGNOR TO L'ETAT FRANCAIS, DÉPARTEMENT DE LA GUERRE, REPRÉSENTÉ PAR LE MINISTRE DE LA GUERRE.

DEVICE FOR MODÉRATING THE SPEED OF DISCHARGE FOR AUTOMATIC FIREARMS.

Application filed August 6, 1923. Serial No. 656,071.

To all whom it may concern:

Be it known that I, JEAN FRÉDÉRIC JULES REIBEL, a citizen of the French Republic, residing 60 Boulevard Blossac, Chatellerault, Vienne, France, have invented new and useful Improvements in a Device for Moderating the Speed of Discharge for Automatic Fire-arms, of which the following is the specification.

10 This invention relates to a device adapted to slow down the speed of firing of automatic fire-arms.

In such fire-arms, the speed of firing depends in fact on the inertia of the breech-block on the one hand, on the characteristic features of the resilient returning member of the said breech-block, on the other hand, and finally on the passive resistances.

20 The speed of firing of an automatic fire-arm could therefore be determined by a judicious choice of the characteristic features of the breech-block and of the returning spring, if the other conditions of construction did not rigorously limit this choice.

25 Automatic fire-arms exist in which the speed of firing depends, besides the above mentioned factors, on the characteristic features of auxiliary members, the only condition of construction of which is provided

30 by the speed of firing chosen for the fire-arm under consideration.

On the other hand, it is obvious that since this speed of firing depends however on the factors first indicated, such an arrangement can serve only for moderating the speed of firing and does not permit its acceleration.

The device forming the subject-matter of the invention is classified in this category 40 of apparatus for moderating the speed of firing, and is characterized in that the period of the reciprocating movement of the breech-block depends on the period of the sustained oscillations of a system composed 45 of a mass movable on a determined trajectory and of a resilient returning member for this mass, the energy for sustaining the oscil-

lations of the said system being supplied by the recoil of the breech-block, or, generally speaking, of the driving member. 50

Of course, the mechanical realization of the system movable mass-returning member can give rise to numerous modifications capable of differing for instance:

(a) by the form of the trajectory imposed to the movable mass: straight line, circumference or any other plane or skew curve;

(b) by the type of resilient returning member used: springs of all kinds, pneumatic or hydropneumatic devices;

(c) by the means used for rendering rigid together, during a variable time and range of movement, the movable mass and the breech-block, during the driving stroke of 65 the latter;

(d) by the means used for causing the period of the reciprocating movement of the breech-block to coincide with that of the oscillation of the movable mass. 70

In order that the invention may be easily understood and to clearly point out the essential characteristic feature above indicated, a form of construction is illustrated by way of example only, in the accompanying drawing. 75

Figs. 1 and 2 are explanatory diagrams of the mechanism.

Figs. 3 and 4 are two elevations, partly in section, of the device mounted on an automatic fire-arm in which the breech-block is controlled by a piston subjected to the action of the gases. 80

Figs. 5 and 6 are views of detached parts.

The form of construction illustrated is 85 more particularly characterized in that:

(a) the trajectory of the movable mass is rectilinear;

(b) the resilient returning member is a spring;

(c) the movable mass is provided with a nose piece which allows it to be drawn along by the breech-block, during its driving stroke, and to separate therefrom after the 90

abutting of this latter, or after withdrawal of the nose piece,

(d) the breech-block or the driving member is provided with a stop tenon, which, at 5 the end of the recoil of the said breech-block, engages with a trigger, the tripping of the latter being controlled by the return of the movable mass, under the action of its returning spring; the movable mass constitutes therefore from this fact an automatic trigger and will be designated by this term hereafter.

Referring to the diagrams of Figs. 1 and 2, it will be seen that 1 designates a tumbler 15 on which acts a spring 2 which constantly tends to compel it to take the position of engagement with the tenon 3 of the breech-block 4 (position illustrated in Fig. 1). At rest, the tumbler 1 is held in withdrawn position by the trigger 5, brought back by the spring 6, and the nose 7 of which presses on the nose 8 of the tumbler 1. The trigger 5 is, moreover, provided with a tenon 9 which abuts against the tenon 10 of the 25 breech-block 4.

The operation when firing in a continuous manner is as follows:

During its recoil, or driving stroke, the breech-block 4 shortly before abutting, engages, through its tenon 10, with the tenon 9 of the trigger 5 and projects the latter rearwardly. The tumbler 1, released, moves to its position of engagement and the breech-block 4 is then immobilized.

35 The trigger 5, thus projected, compresses the spring 6; then, the latter brings it forward again, so that its nose 7 engages with the nose 8 of the tumbler 1, this determining the release of the latter and, consequently, 40 of the breech-block and the firing of the following cartridge, after which the cycle described takes place over again.

It will be seen that, in this manner, the 45 period of the reciprocating movement of the breech-block depends entirely on the period of the sustained oscillations of the system: trigger 5, spring 6, the energy sustaining the oscillations of this system being supplied by the recoil of the breech-block.

50 The period of the oscillations of the system under consideration depending on the mass of the trigger 5 and on the characteristic features of the spring 6, can therefore be determined at will; that is to say it is 55 possible to devise an automatic fire-arm having a determined speed of firing.

In the characteristic features of the spring 6 must be included its initial tension; now, 60 numerous systems for the adjustment of the tension of a coil spring are known. Therefore, the device described allows to adjust the speed of firing.

Figs. 3 to 6 relate to the application of the above described moderating device to an

automatic fire-arm in which the breech-block 65 is controlled by a driving piston 11 subjected to the action of the gases.

As shown in Fig. 5, the automatic tumbler 1 has in section the shape of an inverted U and has, at its end, within the branches, two inclines 8 which are normally in contact with the tenons 7 of the trigger 5 (Fig. 3). The trigger 5 is perforated with a hole in which is arranged the returning spring 6 which, in this case, works under traction; the trigger 5 is, moreover, provided with a nose piece 9 held in raised position by a spring 12 and which can be engaged by the driving tenon 3, during the recoil of the driving piston 11. The said piston moves the trigger 5, this having for effect to engage the nose piece 9 in the tumbler hook, thus releasing the trigger which continues its movement by inertia; before the piston has reached its abutment the tenon 3 passes beyond the tumbler hook, and the tumbler 1, lifted by the spring 12 of the nose piece 9, immobilizes the driving piston.

When the trigger 5 comes in contact with the abutment 13, the spring 6 brings it backward and when the tenons 7 come in contact with the inclines 8, the tumbler 1 is lowered and the piston 11 is again released.

It is obvious that the initial tension of the spring 6 may also be caused to vary, for the purpose of modifying the speed of firing, as previously indicated.

What I claim as my invention and desire to secure by Letters Patent is:

1. In an automatic fire arm, a system the 100 sustained oscillations of which act for giving a determined period to the reciprocating movement of the breech-block of the fire arm in order to regulate the speed of firing of the same, the said system comprising a mass 105 movable on a rectilinear trajectory and subjected to the action of the breech block and of a returning spring, a pivoted tumbler, a stop tenon being provided on the breech-block of the fire-arm so that the said tenon 110 engages with said tumbler when the breech-block is at the end of its driving stroke, the said tumbler being released under the action of the movable mass when it is brought back by its spring, the said movable mass thus 115 constituting an automatic trigger.

2. In an automatic fire arm, a system the 120 sustained oscillations of which act for giving a determined period to the reciprocating movement of the breech-block of the fire arm in order to regulate the speed of firing of the same, the said system comprising a mass movable on a rectilinear trajectory and subjected to the action of the breech block and of a returning spring, a nose piece pivoted 125 on the mass and subjected to the action of a spring, a pivoted tumbler under which the movable mass can engage, a stop tenon ar-

ranged on the breech-block for striking against the nose piece of the movable mass and engaging with the tumbler when the movable mass is engaged under the said tumbler, inclines on this tumbler, other inclines arranged on the movable mass in such a manner as to engage with the inclines of the tumbler, move the latter downward and release the breech block, when the said movable mass is brought back by its spring. ¹⁰

In testimony whereof I have signed my name to this specification.

JEAN FRÉDÉRIC JULES REIBEL.
